UNITED STATES PATENT OFFICE.

EDMUND D. GILBERT, OF PHILADELPHIA, PENNSYLVANIA, ASSIGNOR TO THE S. S. WHITE DENTAL MANUFACTURING COMPANY, OF PHILADELPHIA, PENNSYLVANIA, A CORPORATION OF PENNSYLVANIA.

CAP-CROWN SLITTER.

1,058,743.

Specification of Letters Patent.

Patented Apr. 15, 1913.

Application filed October 2, 1911. Serial No. 652,325.

To all whom it may concern:

Be it known that I, EDMUND D. GILBERT, a citizen of the United States, and a resident of Philadelphia, county of Philadelphia, State of Pennsylvania, have invented 5 certain new and useful Improvements in Cap-Crown Slitters, of which the following is a specification.

My invention relates to cap crown slitters 10 which are employed by dentists for slitting cap crowns upon teeth or teeth roots to facilitate their removal therefrom in case removal becomes necessary.

Implements of the character to which my 15 invention relates include bearing jaws or beaks adapted to bear upon the cusp surface of the cap crown and cutting or slitting jaws or beaks having cutting or slitting points which are adapted to cut or slit the 20 side of such cap crown.

An implement of the character to which my invention relates and the manner or method of its use is illustrated and described in Letters Patent of the United States No. 25 553,718, granted January 28, 1896 to the assignee of Joseph B. Monfort. In the said patent the cutter or slitter is integral with the slitting jaw or beak and it has been found that in use the point of the cutter or 30 slitter is worn away and also that occasionally, through accident, such point is broken or chipped off. In either case, it is necessary to sharpen the cutter thus shortening the same and thereby to some extent destroying the calculated relations between the 35 two beaks. The length of the cutter is thus decreased to such an extent that it becomes necessary for the dentist to discard the implement and replace the same with a new 40 one.

One object of my invention is to provide an implement of this character with novel means for adjustably and detachably connecting a slitting blade or member to the 45 cutting or slitting jaw thereof.

A further object is to provide such an implement with a slitting blade or member which is not only adjustable and detachable

but is also reversible, that is, either of its ends may be employed as a slitting end. 50

In the accompanying drawing I have illustrated one form of a convenient embodiment of my invention but it will be understood that changes in the details of construction may be made within the scope 55 of the claims without departing therefrom.

In the said drawing: Figure 1 is a view in side elevation of a cap crown slitter embodying my invention; Fig. 2 is an edge view thereof looking upwardly in Fig. 1; 60 Fig. 3 is an enlarged side elevation of one end portion of the implement, the slitting jaw or beak being shown in longitudinal section and the slitting or cutting blade being shown in side elevation in proper position with relation to the said jaw or beak; 65 and Fig. 4 is a transverse section of the cutting jaw or beak on the line 4-4 of Fig. 1.

Upon reference to the drawing it will be seen that the implement consists of two 70 main or body members 1 and 2 which cross each other near their forward ends and which are pivotally secured together at their point of crossing or intersection by a pivot 3. The said members are provided 75 with forceps-like handles 4 and 5 and with a bearing jaw or beak 6 and a cutting or slitting jaw or beak 7.

The inner surface of the outer end of the bearing jaw or beak is concaved or curved 80 as indicated at 8 to form a recess for the purpose of providing a more secure bearing or better hold upon the cusp end of the cap crown to be removed than could be obtained if such recess were not present and if the 85 inner side of the said outer end portion of the jaw were smooth or plain.

The outer side of the cutting or slitting jaw or beak 7 is provided with a slot 9 which extends longitudinally thereof and 90 in which a cutting or slitting blade 10 is secured. The said slot does not extend entirely through the jaw 7 so that a thin part 11 of the inner portion thereof is left which covers and protects the inner edge of the 95 portion of the cutting blade 10 which does

not project beyond the jaw or beak 7. The opposite side portions of the jaw 7 are provided with perforations 12 which are adapted to receive screws 13 employed for the purpose of securing and holding the blade 10 in the slot 9. There are two of the said perforations 12.

The central portion of the blade 10 is provided with three perforations 14 any two of which may be placed in alinement with the perforations 12 through the jaw 7 in order that the screws 13 may be passed through the alined perforations. Both ends of the cutting blade 10 are provided with cutting points or edges as indicated at 15 and 16.

In operation the end of the jaw 6 is placed upon the coronal surface or cusp end of the metallic cap crown to be removed, the said end being received in the said recess 8. The cutting end 15 is placed underneath the lower edge of the said cap crown and against the tooth or tooth root and then by compressing the handles 4 and 5 the said crown is easily slit or cut from end to end.

As already pointed out, the cutting edges and points of a cutter or slitter are worn away by use and occasionally are accidentally broken, necessitating sharpening. In the construction embodying my invention when the cutter or slitter, while occupying one position in the slot 9, has been shortened by sharpening so that it does not occupy a correct position with respect to the bearing jaw, the said cutting blade may be adjusted outwardly by removing the screws 13 and moving the blade forwardly. The screws are then replaced to secure the blade in its adjusted position in said slot 9. In case the cutting edge and point 15 becomes shortened to such an extent that it may not be used even after forward adjustment, the ends of the said blade may be reversed so as to bring the cutting edge and end 16 thereof into proper relative position with respect to the bearing jaw or beak 6. Such cutting point or end 16 may be used and adjusted exactly in the same way as has been described in connection with the cutting edge 15.

When the cutting blade is provided with three perforations, as indicated, it will be seen that provision is made for a single adjustment longitudinally of the blade for each end thereof. It will be understood, however, that the number of perforations in the blade may be increased, within limits, and that the number of adjustments thereof may be correspondingly increased.

By reason of the fact that the slot 9 extends throughout the length of the jaw 7 the rear end of the knife, that is to say, the end thereof not in use, is concealed and protected, as is clearly shown in the drawings, not only protecting the hand or hands of a person handling the implement, but also

protecting the portion of the blade itself 65 which is not in use.

When both ends of the cutting blade have been used until they have worn too short to be satisfactory even after adjustment as described, the said blades may be discarded 70 and a new blade substituted therefor.

It will be seen, therefore, that my invention provides not only for the adjustment of a blade in order to prolong the period during which a single blade may be used, but it 75 also provides means whereby when a blade is worn out it may be discarded and a new blade substituted in lieu thereof thus enabling dentists to have on hand at all times an implement with a sharp slitting or cutting point without the necessity of purchasing from time to time an entirely new implement.

Having thus described my invention, I claim:—

1. A cap crown slitter comprising pivoted members having jaws one of which is for contact with the top of a cap crown and the other one of which is provided with a blade for slitting the cap crown at its side, which 90 blade is adjustable lengthwise and is also detachable and reversible, and one side edge of each end portion of said blade being a cutting edge.

2. An implement of the character described, consisting of two members pivoted together intermediate their ends, the said members being provided with jaws, one of the said jaws being for contact with the top of a cap crown of a tooth and the other of said jaws having a slot in its outer edge which extends longitudinally thereof and also having a double-ended blade adjustably and detachably secured in said slot for slitting a cap crown at its side.

3. In an implement of the character described, the combination of two members, a pivot for pivotally connecting the said members at points intermediate their ends, the portions of the said members upon one side of the pivot constituting handles and the portions upon the opposite sides thereof constituting jaws, one of the said jaws being adapted for contact with the top of a cap crown and the other of said jaws being provided with a seat formed therein and having holes extending therethrough across the said seat, a double-ended slitting blade located in the said seat, and having holes therethrough which may be placed successively in alinement with the holes in the said jaw, whereby the said blade may be adjusted longitudinally, and means extending through the holes in the said jaw and in the said slitting blade for securing the latter in position.

4. A cap crown slitter comprising two members pivoted together and having jaws one of which is longer than the other, the

longer jaw being for contact with the top of a cap crown and the other shorter jaw being provided with a slot or groove in its outer edge and having a double-ended slitting

5 blade adjustably and reversibly secured in said slot or groove and both ends of which blade are sharpened and constitute slitting ends for slitting a cap crown at its side.

In testimony that I claim the foregoing as my invention, I have hereunto signed my 10 name this 23rd day of September, A. D. 1911.

EDMUND D. GILBERT.

In the presence of—

GEORGE W. GABRIELL,
W. S. CUNNINGHAM.
